DISINTEGRATING MACHINE

Raffaele Baccellieri, Philadelphia, Pa., assignor to Raffaele Baccellieri and Peter Baccellieri, partners trading as Baccellieri Bros. Mfg. Company, Philadelphia, Pa.

Application July 31, 1931. Serial No. 554,221

1 Claim. (Cl. 146—115)

This invention relates to disintegrating machines, and has for an object to provide a machine having improved means for disintegrating material, such for instance as cheese, although it is to be understood that the invention is not limited to any particular material upon which it is to operate.

A further object of the invention is to provide a disintegrating machine, having a rotating disintegrating disc of improved type.

A further object of the invention is to provide a disintegrating machine having improved means for feeding the material into contact with the disintegrating disc.

15 The invention therefore comprises a disc having disintegrating talons outstanding therefrom, with communicating passages through the disc, a curved chute contiguous to the disc, having a partition therein, with a feeding device slotted to accommodate the partition to feed material to the disc, a driving means for rotating the disc, and a receptacle for receiving the disintegrated material from the disc.

20

The invention is directed to other objects, and
25 possesses other features of novelty and advantage,
some of which, together with the foregoing, will
be hereinafter more fully set forth.

In the drawings:

Figure 1 is a view of the device partly in side elevation and partly in section;

Figure 2 is a view of the machine in top plan, Figure 3 is a plan view of the preferred form of disintegrating disc.

Figure 4 is a plan view of a modified type of
disintegrating disc and

Figure 5 is a sectional view taken on lines 5-5 of Figures 3 and 4.

Like characters of reference indicate corresponding parts throughout the several views.

40 The improved disintegrating machine, which forms the subject matter of this application, comprises a base 10, upon which is erected a housing 11. The housing 11 is preferably open at one end to receive slidably inserted therein a container 12.

45 Mounted upon the housing 11 is a prime mover 13, having a pinion 14 intergeared with a spur gear 15, carried upon the shaft 16 which extends into the passage 17. The passage 17 communicates with the interior of the housing 11 over the 50 receptacle 12, and designed to discharge material thereinto.

55 Mounted upon the shaft 16, is a disintegrating disc 18 or 18'. These disintegrating discs have extending from the face opposite the gear 15 a plurality of talons 19. In the type shown at Figure 3, the talons 19 are arranged spirally about the center opening 20 which receives a fastening member, as the screw 21 to secure the disc to the shaft 16. Each of the talons 19 is arranged at 60 one side of a perforation 22, such perforations

being tapered from the working face of the disc to the back, as indicated more particularly in the enlarged detail sectional view, shown at Figure 5. Merely as lending to the understanding of the construction without attempting to claim method of manufacture, it may be pointed out that these talons are raised by an implement which is driven into the face of the disc, forming the groove 23, and after the talon is so raised, the perforations 22 are drilled contiguous thereto.

The disc 18 or 18' rotates in an opening formed in the side of the passage 17, and communicating with this opening, is a feed chute 24, curved both transversely and longitudinally, both curvatures corresponding to the arcuature of the discs. Within this chute, a partition 25 is erected. A feed follower 26 is fulcrumed at 27 and provided with a handle 28, and necessarily with a slot to accommodate the partition 25.

In operation, the machine will be driven to 80
rotate the discs in the direction indicated by the arrows at Figures 3 and 4 so that each of the perforations 22 is immediately followed by one of the talons. The material to be disintegrated is placed in the feed chute with the follower raised to permit such insertion. The follower is then moved downwardly upon the contained material by pressure exerted upon the handle 28, and this pressure communicated to the follower will force the material against the rotating disc. The partition 25 is an important feature as it tends to 85
prevent the contained material from rotating in consonance with the rotation of the disc and holds it so that the passing talons will each move therefrom its bit, such bit being forced through the perforations 22 into the passage 17, falling therefrom by gravity to the receptacle 12. 90
95

The particular types of discs shown are, as noted in the objects of invention, especially designed for the disintegrating or "grating" of cheese, but there are a great number of other commodities which will be disintegrated by the use of this machine as efficiently as cheese.

The disintegrating machine, herein illustrated, may be modified in various ways without departing from the invention herein set forth and hereinafter claimed.

The invention is hereby claimed as follows:

A disintegrating machine comprising a rotating disc, a plurality of talons outstanding from one face of the disc arranged in a volute series, each of said talons having a curved engaging face and being immediately preceded in the order of rotation by a perforation tapered divergently entirely through said disc, said perforation being preceded by a groove tapered throughout its length with the wider end communicating with the perforation.

RAFFAELE BACCELLIERI.
